UNITED STATES PATENT OFFICE.

FREDERICK S. PINKUS, OF NEW YORK, N. Y.

DESIGN FOR AN ORNAMENTATION OF PILLOW-CASES, &c.

SPECIFICATION forming part of Design No. 20,370, dated December 9, 1890.

Application filed October 27, 1890. Serial No. 369,514. Term of patent 14 years.

To all whom it may concern:

Be it known that I, FREDERICK S. PINKUS, a citizen of the United States, residing in New York, in the State of New York, have invented and produced a new and original Design for Pillow-Cases and Sheeting, of which the following is a specification, reference being had to the accompanying drawings, forming a part thereof.

10 In the accompanying drawings, Figure 1 represents a pillow-case provided with my design, while Fig. 2 is an enlarged detail view of the open-work.

15 My design consists in the ornamentation of the border of the pillow-case or sheet, which is provided with a hemmed edge, consisting of a series of lines of open-work, one of the lines being composed of parallel groups of short threads held apart by two groups of 20 threads at the top and bottom, said groups passing above and below the short groups and

crossing each other in the open spaces between the short groups. Above this lower line of open-work are other lines of open-work, two being shown in the drawings, though 25 more or less may be provided. These upper lines consist of short groups of threads held apart by a double group extending through the center, passing above and below, and crossing each other in the spaces between the 30 groups. Within these lines of open-work a flowering figure is shown composed of leaves, buds, and blossoms of the conventional form.

I claim—

The design for pillow-cases and sheeting 35 herein shown and described.

In testimony whereof I affix my signature in presence of two witnesses.

FREDERICK S. PINKUS.
